UNITED STATES PATENT OFFICE.

WILLIAM H. DAVIS, OF BRONXVILLE, AND FREDRICK E. JOSS, OF BROOKLYN, NEW YORK, ASSIGNEES TO LEKTOPHONE CORPORATION, A CORPORATION OF DELAWARE.

TONE-CONTROL DEVICE FOR TALKING-MACHINES.

1,316,537.

Specification of Letters Patent. Patented Sept. 16, 1919.

Application filed May 9, 1918. Serial No. 233,468.

To all whom it may concern:

Be it known that we, WILLIAM H. DAVIS and FREDRICK E. Joss, both citizens of the United States, residing at, respectively, 5 Bronxville, county of Westchester, State of New York, and borough of Brooklyn, county of Kings, city and State of New York, have invented certain new and useful Improvements in Tone-Control Devices for 10 Talking-Machines; and we do hereby declare the following to be a full, clear, and exact description of the invention, such as will enable others skilled in the art to which it appertains to make and use the same.

15 This invention relates to tone-control devices for talking machines, and in particular for talking machines of the so-called Hopkins-type, wherein the vibrations of the stylus are transmitted by a connecting device 20 to a conical diaphragm of large area, the connecting device comprising a rod or analogous element and a stylus holder. The diaphragm referred to is freely exposed to unconfined air and is so constructed and 25 arranged as to take the place of the usual sound-box and of its associated horn or similar amplifier.

In instruments of the character stated, the diaphragm is carried by a supporting 30 bar which is mounted to swing across the record and is provided with a bore that extends from end to end thereof; said bore receiving the vibration transmission connection, the rod element of which is joined 35 at its rear end to the apex of the diaphragm and at its front end to the stylus holder, the latter being fulcrumed on the front end of the aforesaid bar and disposed partly within the same. It follows, therefore, that 40 the stylus, in traveling along a phonic line, will impart to the diaphragm vibrations corresponding to those recorded in said line, so that the intensity of the vibrations of the diaphragm is dependent upon that of the 45 vibrations passing through or set up in the transmission connection. Consequently, if some means be provided whereby the vibrations of the transmission connection can be damped, the vibrations of the diaphragm, 50 and, hence, the tone of the instrument will be correspondingly affected and will be diminished or increased according as the

damping action exerted upon the transmission connection is increased or decreased.

The present invention aims, therefore, to 55 provide an effective means or device for acting upon the transmission connection in the manner indicated, such action being obtained, according to the illustrated embodiment of the invention, through the agency 60 of a gripping element which is disposed in position to exert a progressive binding or wedging action on the aforesaid connection when shifted in one direction, the operation of this element being effected by means of 65 a device which is rotatably mounted upon the support.

The accompanying drawing represents one form which the invention may take in practice; but it is to be understood that no 70 limitation to the precise structural details thereof is intended nor to be imposed, since modifications of and changes in such disclosure may obviously be made without departing from the scope of the invention as 75 subsequently claimed.

In said drawing:

Figure 1 is a longitudinal vertical sectional view showing the application of the invention to the supporting bar of a Hopkins-type machine;

Fig. 2 is a horizontal section taken on line 2—2, of Fig. 1;

Figs. 3 and 4 are transverse vertical sections taken, respectively, on line 3—3 of 85 Fig. 2 and line 4—4 of Fig. 1;

Fig. 5 is a view similar to Fig. 4 but showing the gripping element in a different position; and

Figs. 6 and 7 are, respectively, a perspective view and a rear elevation of the gripping element.

Referring more particularly to the mechanism illustrated in the aforesaid drawing, 10 indicates generally a swinging support 95 or bar which is mounted to move across the record or its equivalent, and is provided with a bore 11 that extends through it from end to end. The bore 11 receives the transmission rod 12 which, as previously 100 stated, forms one element of the transmission connection, the latter also comprising the stylus holder 13. The rod 12, as usual in Hopkins machines, projects beyond the

ends of the bore 11 and is connected at its rear end to the apex of the conical diaphragm, (not shown), and at its front end to the stylus holder 13, the said holder being connected in turn, with the front end of the bar through the intermediary of a leaf spring 14. None of these features forms any part of the present invention, however, and for that reason extended illustration and description thereof are omitted, it being deemed sufficient to state that the leaf spring 14 provides a resilient mounting for the stylus holder and that the vibrations of the stylus carried by the holder are transmitted from the holder through the rod 12 to the apex of the diaphragm in a manner to move the entire conical portion of the latter bodily. The leaf spring may be mounted in the rod in any desired way, but is preferably capable of adjustment for the purpose of varying the effective length of its exposed end—that is, the portion of the spring between the bar end and the stylus holder.

25 The tone control device is carried by the supporting bar 10, and, in the construction illustrated, is disposed within a chamber 15 into which the front end of the bore 11 of the bar opens, this chamber being constituted by the forward portion of a hollow cylindrical cap or sleeve 16 that is fitted on and extends beyond the bar end, as represented in Figs. 1 and 2. A portion of the stylus holder 13 is also disposed within the said chamber, but the part thereof which actually carries the stylus projects outwardly through an opening 17 in the cap. The said tone control device preferably consists of a sector-shaped member 18, which is cut away centrally from end to end to form a pair of converging jaws 19, located opposite and in spaced relation to each other, and which is provided upon its back with a central, longitudinal rib 20. This rib is slidably fitted in a circumferential slot 21 formed through cap 16, and is suitably fastened to a ring 22 that loosely encircles said cap, so that when the ring is turned in one direction or the other, the sector-shaped member 18 will be shifted endwise correspondingly.

50 The aforesaid member 18 is engageable with the stylus holder 13, which is preferably formed at its rear end with a lateral extension 26, the free end of this extension being adapted to enter the space between the jaws 19 of said member. To provide for a snug fit between the jaws and the extension, as well as to assist in damping the vibrations of the stylus holder and hence, of the transmission rod 12, when the engagement between the holder and the member 18 takes place, the inner sides of the jaws are lined or faced with strips 27 of felt or other material capable of exerting

the required damping action. The space or channel between the jaws 19 is, however, wedge-shaped, as clearly illustrated in Fig. 7, due to the convergence of said jaws, the wide end of such space being disposed opposite the extension to facilitate the entrance of the extension end thereinto, as will be understood. For that reason, the pressure exerted by the jaws of the member 18 upon the extension will increase as the said member moves from its wide end toward its narrow end, and will decrease when movement in the opposite direction occurs. In other words, the member 18 will exert a gripping or binding action upon the stylus holder which gradually increases or progresses as the said member moves from its disengaged position, shown in Fig. 5, to the position shown in Figs. 3 and 4, but will be decreased if the direction of movement be reversed. Hence, it follows that the damping of the vibrations imparted to the stylus holder will be correspondingly progressive, with the result that the vibrations transmitted through the rod connection 12 to the diaphragm will be similarly affected. The maximum damping effect will be obtained, of course, when the extension reaches the narrow end of the channel or passage between the gripping jaws; and, conversely, the vibrations will reach their normal intensity when the gripping member and extension are disengaged, at which time the tone of the instrument will be loudest.

We claim:

1. The combination, with a tubular support, and a vibration transmission connection disposed therewithin; of a single shiftable gripping member within said support for damping the vibrations of said transmission connection with increasing force; and operating means for said gripping member. 100
2. The combination, with a tubular support, and a vibration transmission connection disposed therewithin; of an endwise-movable gripping member within said support for damping the vibrations of said transmission connection with increasing force; and operating means for said gripping member. 110
3. The combination, with a tubular support, and a vibration transmission connection disposed therewithin; of a single shiftable gripping member within said support for damping the vibrations of said transmission connection with increasing force; and a device rotatably mounted on said support and connected to shift said gripping member. 120
4. The combination, with a tubular support, and a vibration transmission connection disposed therewithin; of a single shiftable gripping member within said support for damping the vibrations of said transmission connection with increasing force; and operating means for said gripping member. 125

mission connection with increasing force; and a ring encircling said support and movable around the same, said ring being connected to shift said gripping member.

5. The combination, with a tubular support, and a vibration transmission connection disposed therewithin; of a shiftable member within said support embodying a pair of converging jaws arranged to exert 10 a progressive damping action on said transmission connection from opposite sides thereof; and means for shifting said gripping member.

6. The combination, with a tubular support, and a vibration transmission connection disposed therewithin; of a shiftable gripping member within said support embodying a pair of converging jaws arranged to exert a progressive damping action on 15 said transmission connection from opposite sides thereof; and a device rotatably mounted on the exterior of said support and connected to shift said gripping member.

7. The combination, with a tubular support, and a vibration transmission connection disposed therewithin; of a shiftable, sector-shaped member within said support engageable with said transmission connection between its opposite sides; and means 20 for shifting said member to cause it to exert a progressive gripping action on said transmission connection, thereby to progressively damp the vibrations of the latter.

8. The combination, with a support, and 25 a vibration transmission connection carried thereby and including a stylus holder; of a shiftable member carried by said support for gripping said stylus holder with increasing force to damp its vibrations; and operating 30 means for said gripping member.

9. The combination, with a support, and a vibration transmission connection carried thereby and including a stylus holder; of a shiftable member carried by said support 45 for gripping said stylus holder with increasing force to damp its vibrations; and a device rotatably mounted on said support to adjust said gripping member.

10. The combination, with a support, and 50 a vibration transmission connection carried thereby and including a stylus holder; of a single gripping member carried by said support and provided with a pair of converging jaws arranged to engage said transmission 55 connection from opposite sides thereof; and means for shifting said gripping member to cause its jaws to exert a progressive binding action on said transmission connection to damp its vibrations.

11. The combination, with a support, and 60 a vibration transmission connection carried thereby and including a stylus holder; of a single gripping member carried by said support and provided with a pair of converging 65 jaws arranged to engage said transmission

connection from opposite sides thereof; and a device rotatably mounted on said support for shifting said gripping member to cause it to exert a progressive damping action on said transmission connection.

70

12. The combination, with a support, and a vibration transmission connection carried thereby and including a stylus holder; of a shiftable member carried by said support having an inclined portion for engagement 75 with the stylus holder to exert a progressive wedging action thereon so as to damp the vibrations of said holder; and operating means for said shiftable member.

13. The combination, with a support, and 80 a vibration transmission connection carried thereby and including a stylus holder; of a single gripping member carried by said support and provided with a pair of converging jaws arranged to engage said stylus holder 85 from opposite sides thereof; and means for shifting said gripping member to cause its jaws to exert a progressive wedging action on said stylus holder to damp its vibrations.

14. The combination, with a support, and a vibration transmission connection carried thereby and comprising a stylus holder having an extension and a rod connected at one end to said extension; of a shiftable gripping member carried by said support and 95 arranged to engage said extension with increasing force to damp the vibrations of the stylus holder; and operating means for said 90 gripping member.

15. The combination, with a support, and 100 a vibration transmission connection carried thereby and comprising a stylus holder having an extension and a rod connected at one end to said extension; of a shiftable gripping member carried by said support and 105 provided with a pair of converging jaws arranged to engage said extension from opposite sides thereof; and means for shifting said gripping member to cause its jaws to exert a progressive wedging action on said 110 extension to damp the vibrations of the stylus holder.

16. The combination, with a tubular support, and a vibration transmission connection disposed therewithin and comprising a 115 stylus holder having an extension and a rod connected at one end to said extension; of a shiftable gripping member within said support arranged to engage said extension with increasing force to damp the vibrations 120 of the stylus holder; and operating means for said gripping member.

17. The combination, with a tubular support, and a vibration transmission connection disposed therewithin and comprising a 125 stylus holder having an extension and a rod connected at one end to said extension; of a shiftable gripping member within said support arranged to engage said extension with increasing force to damp the vibrations 130

of the stylus holder; and means rotatably mounted on said support and connected to operate said gripping member.

18. The combination, with a tubular support, and a vibration transmission connection disposed therewithin and comprising a stylus holder having an extension and a rod connected at one end to said extension; of a shiftable gripping member within said

support arranged to engage said extension 10 with increasing force to damp the vibrations of the stylus holder; and an annular member rotatably mounted on said support and connected to operate said gripping member.
